UNITED STATES PATENT OFFICE.

CLYDE D. LOVE, OF COSHOCOTON, OHIO.

SUN-DIAL.

1,289,837.

Specification of Letters Patent. Patented Dec. 31, 1918.

Application filed March 30, 1917. Serial No. 158,658.

To all whom it may concern:

Be it known that I, CLYDE DARWIN LOVE, a citizen of the United States, and a resident of Coshocton, in the county of Coshocton, 5 ton and State of Ohio, have invented a certain new and useful Improvement in Sun Dials, of which the following is a specification.

The present invention relates to sun dials, 10 and has for an object to provide a device of this nature which may be folded or collapsed into compact form for easy handling and transportation.

Another object of the invention is to provide a sun dial which may be used as an advertising novelty or sign; which may be easily mounted on various kinds of supports; which is adjustable to accommodate the device to various shapes and positions 20 of support for correctly presenting the sun dial for use; and which may be made as a part of a small building structure, or the like.

The invention further aims at the provision of a sun dial having a novel bracket for holding the dial at the desired inclination, and which may be adjusted to hold the dial at various angles relatively to the plane of inclination; having a novel means for adjustably supporting the gnomon, and ascertaining the correct positioning of the same dependent upon the latitude in which the sun dial is placed; and having means for adjusting the sun dial for any longitude, and 35 to compare with the time used in any locality, or the various standard times.

The above, and various other important objects and advantages of this invention, will be in part described, and in part understood, from the following detailed description of the present preferred embodiment, the same being illustrated in the accompanying drawing wherein:

Figure 1 is a front elevation of a sun dial constructed according to the present invention.

Fig. 2 is a side elevation of the same.

Fig. 3 is a vertical section taken through the sun dial on the line 3—3 of Fig. 2, showing the back plate thereof and the parts carried thereby.

Fig. 4 is a horizontal section taken on the line 4—4 of Fig. 2.

Referring to this drawing, wherein like 65 parts are designated by similar characters of reference, 10 designates the back plate

which is adapted to be arranged substantially vertically, and may be provided at its upper end and across its rear face with an attaching strap 11 projecting beyond the 60 lateral edges of the back 10 and suitably apertured to receive therethrough screws or the like for attaching the back 10 to a support.

The back 10 may be of any suitable configuration, and as shown is relatively wide at its lower end. A second attaching strap 12 is secured across the rear face of the back 10 and projects beyond the lateral edges thereof and is apertured for the reception of additional screws or the like for rigidly holding the back 10 in position. The back 10 is provided upon its outer side, and at its upper end, with a pair of vertically alining and spaced-apart eyes 13 and 14 adapted to receive a headed pivot pin 15 carried therethrough.

The lower-eye 14 forms a pivot upon which is mounted a locking lever 16, the latter being preferably in the form of a flat strip of 80 metal lying against the outer face of the back 10 and, when in locked position, engaging at its upper end beneath the pivot pin 15 and extending in substantially a straight line downwardly from the eye 14. 85 The lower end of the locking lever 16 is turned at right angles to provide a finger-hold 17, by means of which the lever 16 may be flexed outwardly from the back 10 at its lower end to escape a retaining pin 18 projecting from the outer surface of the back. 90 A stop pin 19 also projects outwardly from the back 10 at a point adjacent to the eye 14 for engagement with the adjacent edge of the locking lever 16 when in upright locking 95 position as shown in Fig. 3. The upper end of the lever 16 is bent outwardly at substantially right angles to provide a supporting lip 20 which is adapted to lie in slightly spaced relation from the upper 100 eye 13.

The back 10 carries a dial or base plate 21 having upon its upper end and projecting from its rear face an eye 22 through which the pivot pin 15 is adapted to engage. 105 The eye 22 is adapted to be positioned between the eyes 13 and 14, and the dial 21 is held in raised position to engage the eye 22 against the eye 13 while the locking lever is swung into locking position. The lip 20 110 of the lever engages the eye 22 and holds the latter in raised position. Hinged upon

the rear face and lower end of the dial 21, is a strap 23, the latter being pivoted at 24 upon the inner end of a segment 25 which in turn is hingedly connected to the lower end 5 of the back 10. The strap 23 is adapted to traverse the upper side of the segment 25 to support the dial 21 in various laterally adjusted positions, the dial swinging about the pin 15 at its upper end. The segment 10 25 is provided near its outer end with an arcuate slot 26 formed on an arc, the center of which is the pivot 24, and through which projects the stem of a bolt 27 carrying a winged nut upon its free end for binding engagement 15 against the opposite side of the segment plate 25 to bind the strap thereto when adjusted. The bracket thus formed by the segment or plate 25, and the strap 23, is hinged at opposite ends to the back and 20 to the dial, and any downward movement of the dial 21 with respect to the back 10 draws these members together so as to collapse the device. The locking lever 16 holds the dial raised and in extended position. 25

A gnomon 28 is adjustably mounted upon a foldable bracket 29 secured to the outer face of the dial 21. The bracket 29 may be of any suitable configuration, and is disclosed in the present instance as in the form 30 of a substantially triangular casting of open construction and provided with pivotal projections or trunnions 30 at its upper and lower ends for engagement in loops or eyes 35 projecting outwardly from the dial 21 and in vertical register. The bracket 29 is adapted to swing in one direction flat against the outer face of the dial 21, and is held in a true outstanding perpendicular position 40 with respect to the dial 21 by means of a stop lug 32 projecting laterally from the inner edge of the bracket 29 in a direction opposite to that in which the bracket may be 45 swung down against the dial. The lug 32 is apertured, as shown in Fig. 4, and may be provided with a screw or other fastening device for holding the bracket 29 from collapsing. 50

The wider end of the bracket 29 is directed downwardly, and the gnomon 28 is pivotally mounted upon the lower outer corner of the bracket by means of a clamping bolt 33 which projects laterally from the bracket and is provided with a winged nut, 55 or the like for binding engagement against the side of the gnomon 28. The gnomon 28 may be in the form of a sheet of metal suitably stamped, and which is adapted to lie flat against one side of the bracket 29, the 60 latter being flattened at said side to provide a relatively flat bearing surface for the gnomon 28. The gnomon 28 is substantially triangular in form and is mounted on the bracket 29 with its hypotenuse edge uppermost, and with the clamping bolt 33 engag-

ing through an arcuate slot 34 formed on an arc whose center is the upper corner or apex of the gnomon 28. Said upper corner or apex is pivoted, by means of a pin 35, to the upper corner of the bracket 29 and the 70 gnomon is adapted to swing about said pin 35 into various angles relatively to the dial 21, as indicated on the scale of graduations 36 extending along one marginal edge of the slot 34. The pivot bolt 33 constitutes the 75 fixed marker for co-operation with the graduations 36 to determine the positioning of the gnomon 28.

The outer face of the dial 21 is provided with a circular substantially marginal row 80 of roman numerals printed, painted, or otherwise suitably placed upon the dial 21. The numerals are arranged successively from I to XII, and in anti-clockwise fashion. It will be noted that the number XII is located at the base or bottom of the dial 21, and that the numeral VI occurs twice at the top of the dial, one at each side of the vertical center of the dial. This duplication of the numeral VI at opposite sides of the dial 90 provides a true reading at this hour anti-meridian and post-meridian.

The dial 21 disclosed in the present instance is substantially circular in contour, but may be of any desired form to display 95 information or advertising matter, and the back 10 may be of any desired length or size to project or otherwise extend into view for carrying advertising matter.

The dial-supporting bracket at the lower 100 end of the back 10 is preferably of such length that when extended it supports the dial 21 at an inclination of substantially fifteen degrees, though of course this inclination will be varied according to the north 105 and south positions of the sun dial. The dial 21 is adapted to face southward, and in order to correctly position the same the strap 23 may be adjusted over the face of the segment 25 and clamped by the bolt 27 110 into adjusted position. Thus, the supports A, which may be a building or the like, need not face exactly south for supporting the sun dial. The gnomon 28 is swung about the pivot pin 35 to adjust the same, according to the scale 36, to correspond to the latitude in which the sun dial is placed. The back 10 is preferably secured to the support A by means of screws or the like, and a plumb line 115 may be employed for determining the exact 120 positioning of the back to place the upper and lower supports in true vertical alignment.

It will be noted that both the brackets carried by the back 10, and the bracket carried by the dial 21, are foldable or collapsible so that the device may be folded into relatively small compact form for easy handling and shipment. The device may be economically constructed from wood, sheet 125 130

metal and castings, and the parts are relatively small, few in number and easily assembled.

To collapse the device it is only necessary to swing the bracket 29 against the outer face of the dial 21, and to swing the locking lever 16 about the eye 14 to release the eye 22 and draw the latter downwardly along the pin 15. This downward movement of the eye 22 draws the dial 21 downwardly and swings the bracket thereof down against the back 10. Access may now be readily had to the pivot pin 15 for withdrawing the same upwardly from the eyes 13, 14 and 22.

15 It is of course understood that various changes and modifications may be made in the details of construction of the above-specified described sun dial without departing from the spirit of the invention, and being restricted only by the scope of the following claims.

I claim:—

1. In a sun dial, the combination of a dial, a bracket adjustably mounted upon the outer face of the dial and adapted to be collapsed thereagainst, a gnomon pivotally and adjustably mounted upon the bracket, and means for securing the gnomon in adjusted positions.

30 2. In a sun dial, the combination of a back, a dial, a bracket hingedly mounted at its opposite ends on the back and on the dial, said bracket being adapted to be folded against said back to draw the dial thereagainst when the latter is moved longitudinally of the back, and means for holding the dial in adjusted position when said bracket is extended.

3. In a sun dial, the combination of a back, a dial, a two-part hingedly connected bracket hinged at opposite ends to the back and to the dial, means for supporting the dial in extended positions from the back, and means for securing the dial in various laterally adjusted positions upon said bracket.

4. In a sun dial, the combination of a back, a dial, an adjustable bracket connecting the dial to the back and adapted to be collapsed against the latter, a gnomon, and a collapsible bracket connecting the gnomon to the dial and adapted to hold the gnomon against the outer face of the dial.

5. In a sun dial, the combination of a back, a dial, a sliding pivotal connecting means between the back and the upper end of the dial, a bracket hingedly connected at one end to the back and at its opposite end to the lower end of said dial, said dial being adapted to swing downwardly to collapse the bracket against said back and move the dial thereagainst, means for holding the dial in raised position to extend said bracket, and a gnomon carried upon the outer face of said dial.

6. In a sun dial, the combination of a back, a dial, a sliding pivotal connecting means between the upper ends of said back and the dial, a bracket pivotally connected at opposite ends to the lower extremities of said back and said dial, means for holding said dial in raised position to extend said bracket, a second bracket pivotally mounted upon the outer face of said dial, means for supporting said second bracket in outstanding position from the dial, and a gnomon adjustably mounted upon said bracket.

7. In a sun dial, the combination of a back, a pair of vertically aligned spaced-apart eyes projecting outwardly from the back, a dial, a rearwardly projecting eye carried upon the upper end of the dial, a pivot pin adapted for engagement downwardly through said eyes of the back and said eye of the dial to hold the latter between the eyes of the back, a bracket hingedly connected at its opposite ends to the back and to the dial at a point below said eyes, said bracket being relatively long to advance the lower end of the dial outwardly from the upper end thereof, a locking lever mounted on said back and adapted to engage beneath the eye of said dial to hold the latter in raised position, and means for holding said lever in locked position.

8. In a sun dial, the combination of a back, a dial, a pivot pin mounted on said back, an eye projecting rearwardly from the dial for engagement upon the pivot pin and adapted to move vertically thereover, a relatively long bracket hingedly connected at opposite ends to the back and to the dial, a locking lever pivotally mounted upon said back and provided with a retaining lip for engagement beneath said eye to hold the same in raised position on the pin and to hold said bracket extended, and means for holding said locking lever in locked position.

9. In a sun dial, the combination, of a back, a dial, and means connecting said dial to said back to permit the dial to be swung about a vertical axis or collapsed to lie substantially parallel with the back.

10. In a sun dial, the combination, of a back, a dial, means connecting said dial to said back to permit the dial to be swung about a vertical axis or collapsed to lie substantially parallel with the back, a bracket pivotally connected to the dial and adapted to be collapsed against the face of the dial, and a gnomon pivotally connected to said bracket for movement about a horizontal axis.

11. In a sun dial, a dial, a bracket pivotally connected to the dial and adapted to be collapsed against the face of the dial, and a gnomon pivotally connected to the bracket for movement about an axis transversely of the axis of the bracket.

12. In a sun dial, the combination, of a back, a dial, means connecting said dial to said back to permit the dial to be swung about a vertical axis or collapsed to lie substantially parallel and in close proximity to the back, a locking lever mounted on said back to lock said dial in an outward position, and means for holding said lever against accidental movement.
- 10 13. In a sun dial, the combination, of a back, a dial, means connecting said dial to said back to permit the dial to be swung

about a vertical axis or collapsed to lie substantially parallel with and in close proximity to the back, a locking lever carried by 15 said back for locking said dial in an outward position, with respect to the back, a bracket pivotally connected to the dial and adapted to be collapsed against the face of the dial, and a gnomon pivotally connected 20 to the bracket for movement about an axis transverse to the axis of said bracket.

CLYDE D. LOVE.
